(57) **CLAIM**

The ornamental design for a vehicle window with an animated graphical user interface, as shown and described.

DESCRIPTION

FIG. 1 is a front view of a first embodiment of a vehicle window with a first image of an animated graphical user interface showing our new design;

FIG. 2 is a front view thereof with a second image;

FIG. 3 is a front view thereof with a third image; and FIG. 4 is a front view thereof with a fourth image.

FIG. 5 is a partially enlarged front view thereof along the lines 5-5 of FIG. 1;

FIG. 6 is a partially enlarged front view thereof along the lines 6-6 of FIG. 2;

FIG. 7 is a partially enlarged front view thereof along the lines 7-7 of FIG. 3; and

FIG. 8 is a partially enlarged front view thereof along the lines 8-8 of FIG. 4.

FIG. 9 is a front view of a second embodiment of a vehicle window with a first image of an animated graphical user interface showing our new design;

FIG. 10 is a front view thereof with a second image;

FIG. 11 is a front view thereof with a third image; and FIG. 12 is a front view thereof with a fourth image.

FIG. 13 is a partially enlarged front view thereof along the lines 13-13 of FIG. 9;

FIG. 14 is a partially enlarged front view thereof along the lines 14-14 of FIG. 10;

FIG. 15 is a partially enlarged front view thereof along the lines 15-15 of FIG. 11 and

FIG. 16 is a partially enlarged front view thereof along the lines 16-16 of FIG. 12.

FIG. 17 is a front view of a vehicle that includes the vehicle window shown in FIG. 1;

FIG. 18 is a right side elevational view thereof, wherein FIGS. 1-8 are viewed from the line C-C of FIG. 18 at the lines A-A of FIG. 17 and the lines B-B of FIG. 18.

FIG. 19 is a front view of a vehicle that includes the vehicle window shown in FIG. 9; and,

FIG. 20 is a right side elevational view thereof, wherein FIGS. 9-16 are viewed from the line C-C of FIG. 20 at the lines A-A of FIG. 19 and the lines B-B of FIG. 20.

(Continued)

The dot-dash broken lines, which demarcate portions of a vehicle window, define the boundaries of the claimed design and form no part thereof. The even-dash broken lines, which illustrate portions of a vehicle, form no part of the claimed design. The portions of the graphical user interface shown in faded tone beyond the perimeter of the dot-dash broken lines form no part of the claimed design.

The appearance of the transitional image sequentially transitions between the images shown in FIGS. 1-4 and 5-8 in the first embodiment, FIGS. 9-12 and 13-16 in the second embodiment. The process or period in which an image transitions to another forms no part of the claimed design.
